UNITED STATES PATENT OFFICE

2,091,820

PROJECTOR

Johannes Kiefer, Berlin-Charlottenburg, Germany, assignor to General Electric Company, a corporation of New York

Application November 18, 1935, Serial No. 50,453
In Germany December 6, 1934

1 Claim. (Cl. 240—47)

My invention relates to projectors and more particularly to light projectors having a light source enclosed in a glass envelope such as for example, incandescent filament lamps or gaseous discharge lamps.

One object of my invention is to provide an improved apparatus for cooling such lamps during operation.

For a better understanding of my invention, together with other and further objects thereof, reference is had to the following description taken in connection with the accompanying drawing, and its scope will be pointed out in the appended claim.

15 In the accompanying drawing I have illustrated, in Fig. 1, one embodiment of my invention comprising a projector lamp mounted upon an improved support through which a cooling medium is supplied to cool the lamp. Fig. 2 is a 20 side view of the support, and Fig. 3 is a sectional view looking in the direction of the arrows 3—3 in Fig. 1.

Referring to the drawing in detail, I have illustrated a lamp support comprising a tubular stem 4 terminating in branches 5 and 6 which are angularly spaced with respect to each other. I have illustrated only two branches but it is obvious that any number may be employed. A collar 7, as illustrated in Fig. 3, is attached to 30 the branches 5 and 6 respectively at right angles to the axis of the stem 4. The collar is provided with a removable portion 8 which is attached to the collar in any convenient manner such as, for example, by means of screws 9 and 10. A lamp socket 11 is supported by the collar 7 and in turn supports a lamp 12. As above stated, this lamp may be either a gaseous discharge lamp or an incandescent filament lamp, but preferably the latter, because it approaches more nearly a point

source of intense light which is specially suited for projection purposes. The envelope for this type of lamp is as a rule made of glass which due to the intense heat developed during operation of the lamp rises to temperatures high 5 enough to soften the glass. In order to avoid this, some cooling means must be provided which will not interfere with the emission of the light from the lamp and simultaneously will be of simple construction.

10 The tubular branches 5 and 6 change their direction beyond the collar 7 and are thereafter parallel to each other and to the socket 11. The branches terminate in nozzles 13 and 14 which extend substantially to the edge of the lamp 15 socket 11. The nozzles are arranged to project a narrow film of air and to project this film along the surface of the lamp. The nozzles are made sufficiently broad so that the sheets of air projecting from the nozzle substantially envelop 20 the lamp. During operation of the lamp 12, air is supplied to the stem 4 in any convenient manner such as through a rubber hose, for example, and is distributed to the branches 5 and 6, and finally projected from the nozzles 13 and 14. 25

A reflector 15 for the lamp may be supported from the nozzle 13 by means of a lug 16, attached to the nozzle 14, and by an adjustable rod 17.

What I claim as new and desire to secure by Letters Patent of the United States is:

In a light projector, the combination of a lamp, a support therefor comprising a tubular member terminating in a plurality of branches, a collar attached to said branches, a socket attached to said collar, said branches being provided with nozzles directed toward the surface of said lamp whereby a cooling medium may be projected over the surface of said lamp.

JOHANNES KIEFER.
